UNITED STATES PATENT OFFICE.

FRANKLIN E. ARNDT, OF GALION, OHIO, ASSIGNOR TO THE GALION IRON WORKS AND MANUFACTURING COMPANY, OF GALION, OHIO.

HOISTING AND DUMPING BUCKET.

1,152,472.

Specification of Letters Patent.

Patented Sept. 7, 1915.

Original application filed April 8, 1914, Serial No. 830,470. Divided and this application filed March 9, 1915. Serial No. 13,180.

To all whom it may concern:

Be it known that I, FRANKLIN E. ARNDT, citizen of the United States, residing at Galion, in the county of Crawford and State 5 of Ohio, have invented certain new and useful Improvements in Hoisting and Dumping Buckets, of which the following is a specification.

This application is a division of an application filed by me April 8, 1914, Serial No. 830,470, the invention claimed herein being directed to the provision of novel means for opening a hoisting and dumping bucket to discharge its contents and then restoring it 15 to its former condition to receive a second load.

The invention is fully illustrated in the accompanying drawings in which—

Figure 1 is a side elevation of a hoisting 20 and dumping apparatus in which my improved bucket is used. Fig. 2 is a side elevation of the bucket showing the bottom open. Fig. 3 is a view showing the manner in which the bucket is closed, the bucket 25 being shown in section. Fig. 4 is a front elevation of the bucket.

Referring more particularly to the drawings, 2 designates the rails of a railway track and 3 a bin disposed at the side of the 30 track and mounted upon concrete posts 4, or other suitable supports. The bin may be of any suitable form and is not to be limited to the illustrated details thereof.

Beneath the track and extending parallel 35 to the bin is formed a chute 5 having an inclined bottom which extends outward to a point beyond the track and discharges into a pit 7. This pit has vertical side walls and an inclined end wall.

40 The discharge of material from the chute 5 is controlled by certain gates or spouts which are more fully illustrated and described in my pending application, Serial No. 830,469, filed on the 8th day of April, 45 1914, but it may be said, generally speaking, that the discharge of material from the chute is controlled in the first place by means of a vertically shiftable sliding gate 8 operated by a lever 9, and is still further controlled by a spout 10, which is pivoted to the lower end of the chute. When the spout is turned up to the position shown in full lines in Fig. 1 it will prevent the discharge of material from the chute and when the spout 50 55 is turned down to the position shown in

dotted lines it will discharge material into the middle of a bucket disposed at the bottom of the pit 7. The operation of this pivoted spout 10 is controlled by means of a lever 12. These levers 9 and 12 are mounted in a suitable framework 13, which is shown as braced from the end walls of the pit 7 by means of a brace 14.

Mounted upon the side walls of the bin and extending upwardly therefrom are the 60 uprights 15 and 16 which are preferably made of angle iron or other suitable material of like character, and which carry at their upper ends the transverse braces 17, these braces in turn supporting a longitudinally extending I-beam 18 which is disposed approximately above the middle plane of the bin. The vertical angle irons 15 and 16 are laterally braced as desired and may be also braced by diagonal struts. The I-beam 18 constitutes a track upon which is mounted the shiftable carriage 21. This carriage is adapted to roll upon the flanges of the I-beam 18 and carries a pulley 22 over which passes a cable 23. One end of this cable is attached to the carriage 21 in any suitable manner, and the other end of the cable, after passing over the pulley 22, extends longitudinally beneath the I-beam 18 70 and passes around a sheave 25, then passes over a vertically disposed pulley 26 and extends downwardly to a suitable guide pulley and thence passes over a winding drum 28 75 operatively connected to any suitable engine 80 85 90 95 100 105 110 29. This winding drum is of any ordinary form and is driven in any desired manner, and is adapted to be thrown into and out of operative engagement with the engine by means of the usual clutches controlled by the lever 30 in a manner obvious to those skilled in the art. The cable 23 between the pulley 22 and the point of attachment 24 passes through a block 31 from which the bucket 32 is swingingly supported. This bucket may have any desired shape but is preferably rectangular in form and is provided with a hinged bottom 33. A slotted link 34 which is connected at one end to the hinged bottom 33 limits the downward swing of the bottom, there being a pin 35 formed upon the body of the bucket which extends into the slot of this link. It will be obvious that one or more links may be used for this purpose. Attached to the hinged bottom 33 adjacent its edge is a

transversely extending angle iron 36 adapted to be engaged by a spring latch 37. This latch is in the form of an upwardly extending rod, the lower end of which is formed with a detent 38 adapted to engage over the angle iron 36 when the bottom is closed, this detent being formed with a beveled face. Rods 37 are pivoted at 39 and extend upward to a point above the top of the bucket. A spring 40 urges the upper end of each rod against the stop 41 and when the upper end of the rod is brought against said stop, the detent end of the latch or rod will engage with the angle iron 36, which constitutes a keeper. The bail 42 is rigidly fixed to the bucket in any suitable manner.

For the purpose of opening the bottom 33 to cause a discharge of the contents of the bucket, I mount upon the I-beam 18 bucket-tripping arms 43 which extend laterally so as to be disposed within the path of movement of the upper ends of the latches 37, these tripping arms being so disposed upon the I-beam 18 that they will cause the bucket to discharge into the center of the bin.

For the purpose of closing the bottom of the bucket upon a return movement of the bucket after having discharged its contents, I provide a bucket-closing device shown in Figs. 1 and 3. This consists of a transverse rocking shaft 44 upon which are mounted the upwardly extending fingers 45, these fingers being rounded in one direction. A spring 46 urges the fingers 44 to the position shown in full lines in Fig. 3, movement in this direction being limited by a stop 47. Now, as the bucket moves away from the bucket-tripper 43 the bottom of the bucket will engage with the fingers 45 and these, riding upon the bottom of the bucket will cause it to close, the latching device engaging the angle iron keeper as soon as the bucket is closed. Upon a movement of the bucket toward the bucket-tripper after it has been drawn up to a position above the top of the bin, the fingers 45 will yield and shift to the position shown in dotted lines in Fig. 3, thus permitting the bucket to pass.

It will be seen from Fig. 1 that the I-beam 18 is extended beyond that side wall of the bin which confronts the track 2, so that this projecting end of the I-beam 18 overhangs the pit 7.

The carrier is normally urged to a position upon the projecting extremity of the I-beam 18 by means of a counter-weight. This counter-weight is mounted upon a cable 73 which is attached to the carrier and thence passes over suitable sheaves mounted upon the beam 18 and thence downward where it is attached to the counter-weight 75. The action of this counterweight is to return the carriage to the position shown in Fig. 1 after the bucket has been discharged.

The operation of my invention is as fol-

lows: The contents of the car on tracks 2 is discharged into the chute 5. Assuming that the bucket 32 is lowered, then the operator by means of the levers 9 and 12 first turns the spout 10 to the position shown in dotted lines in Fig. 1 and then raises the cut-off 8. This permits the contents of the chute 5 to be discharged into the bucket 32, it being observed that the spout 10, when lowered, extends over the bucket and discharges into the middle thereof. Just before the bucket is filled the cut-off 8 is lowered. The spout 10 is then raised and the hoisting drum 28 is then operated, winding up the cable 23 and raising the bucket from the pit 7. When the bucket has been raised to such height that a head on the block 31 is forced into the carrier, the carrier will be released and the continued pull upon the cable 23 will cause the carrier to travel laterally upon the track 18 until the tripping members 43 engage the upper ends of the bucket latches 37. The bottom of the bucket will then be released and the weight of its contents will cause the opening of this bottom and the contents will be discharged. When the winding drum 28 is released from its engagement with the clutch and allowed to run free, the counter-weight will cause the carrier to return upon the track, and as the bucket returns, the bucket closer 45 will engage the bottom and close it. When the carrier has returned nearly to its normal position, the block 31 will be released and the weight of the bucket will cause the bucket to drop until it is once more at the bottom of the pit 7, whereupon the operation may be repeated.

It will be noted that the mechanism used by me is very simple and positive in its action. It does not readily get out of order. It has been found thoroughly effective in practice and it requires only two operators to control the discharge of material from the chute 5 into the bin. One of these operators will handle the levers 9 and 12 while the other operator will handle the clutch lever 30. It is obvious, however, that only one operator is absolutely necessary as the hoisting engine may be disposed sufficiently adjacent the levers 9 and 12 to permit one operator to handle all the levers.

Having thus described the invention, what is claimed as new is:

1. In an apparatus of the character described, an overhead track, a bucket shiftable along the track and having a hinged bottom, a latching member mounted on the bucket and engaging the bottom to hold the same closed, a tripping member mounted upon the track in the path of the latching member to engage the upper end of the same and release said member from the bottom of the bucket, and means below the track in the path of movement of the bucket yieldable in one direction to permit movement of the

bucket and unyielding in the opposite direction to engage the bottom of the bucket and urge the same into reengagement with the latching member.

5 2. In an apparatus of the character described, an overhead track, a bucket shiftable along the track and having a hinged bottom, a spring-actuated latching member on the bucket holding the bottom closed and 10 projecting above the upper end of the bucket, a tripping member mounted upon the track and disposed in the path of the upper end of the latching member to release said member and permit the bottom of 15 the bucket to drop, and fingers disposed in the path of return movement of the bucket to engage the bottom thereof and close the same, said fingers yielding in one direction to permit movement of the bucket to a 20 dumping position and held from movement in the opposite direction to cause the closing of the bottom.

3. In an apparatus of the character described, an overhead track, a bucket shiftable along the track and having a hinged bottom, a spring-actuated latching member mounted on the bucket and holding the bottom closed and projecting beyond the upper end of the bucket, a tripping member 25 mounted upon the track in the path of the upper end of the latching member to release said member and permit the bottom of the bucket to drop, and means disposed in the path of the bucket for causing the closing 30 of said bottom, said means comprising a transversely extending rock shaft, angular fingers mounted upon the shaft and having curved extremities, springs acting to permit the shaft to be rotated in one direction to 35 permit passage of the bucket past the fingers and to return the fingers to a vertical position to engage the bottom of the bucket upon its return movement and thereby close the same.

45 4. In an apparatus of the character described, an overhead track, a bucket shiftable along the track and having a hinged bottom, spring actuated latching members pivotally mounted upon the sides of the 50 bucket, the lower ends of said members providing detents engaging the bottom of the bucket to hold it closed and the upper ends of the members projecting above the upper end of the bucket on each side thereof, tripping 55 members mounted upon the track and projecting downward therefrom in the path of movement of the upper ends of the latching members to release said members and permit the bottom of the bucket to drop, 60 and fingers disposed in the path of movement of the bottom of the bucket yielding in one direction to permit the movement of the bucket past the fingers to a dumping posi-

tion and unyielding in the opposite direction to engage the bottom of the bucket and 65 close it.

5. In an apparatus of the character described, a track, a bucket adapted to be shifted along said track and having a hinged bottom, a spring actuated latching member 70 holding the bottom closed, a tripping member disposed in the path of movement of the latching member on the bucket to thereby release the latching member when the bucket has reached a dumping position to permit 75 the bottom of the bucket to drop, and upwardly projecting fingers disposed in the path of movement of the bottom of the bucket and yielding in one direction to permit the passage of the bucket past the fingers to a dumping position and unyielding 80 in the opposite direction to cause the bottom of the bucket to ride upon the fingers and close.

6. In an apparatus of the character described, a track, a bucket shiftable along the track and having a hinged bottom, a latch mounted upon the bucket and engaging the bottom to hold it normally closed, 85 tripping devices mounted on the track to engage the latch and release the same from the bottom, a rock shaft mounted below the path 90 of movement of the bucket, fingers projecting from the said rock shaft into the path of movement of the bottom of the bucket whereby said fingers will bear directly against the bottom of the bucket on the return movement thereof and close the same, means for permitting the fingers to 95 yield to movement of the bucket in one direction, and means for limiting the movement of the fingers in the opposite direction.

7. In an apparatus of the character described, a track, a bucket shiftable along the track and having a hinged bottom, a latch mounted upon the bucket and engaging the bottom to hold it normally closed, tripping devices mounted on the track to engage the latch and release the same from the bottom, a rock shaft mounted below the path 100 of movement of the bucket, a finger projecting upwardly from said rock shaft into the path of movement of the bucket, a spring arranged at one side of the rock shaft and bearing upon said finger to hold the same yieldably in position to engage the bottom of the bucket, and a stop projecting from the rock shaft at an angle to said finger and arranged to limit the movement of the rock shaft under the influence of said spring 105

In testimony whereof I affix my signature in presence of two witnesses.
